LAMP OR SIMILAR ARTICLE

Arnold Goldstein, 3363 Trexler Blvd., Allentown, Pa.

Filed Sept. 9, 1959, Ser. No. 57,491

Term of patent 14 years

(Cl. D48—20)

Figure 1 is a perspective view of a lamp or similar article showing my new design.

The dominant features of my design reside in the portions shown in full lines.

I claim:

The ornamental design for a lamp or similar article, substantially as shown and described.
